UNITED STATES PATENT OFFICE.

JOHN P. WEIS, OF NYACK, NEW YORK, ASSIGNOR TO LUCIUS N. LITTAUER, OF GLOVERSVILLE, NEW YORK.

TOP FEED OR RUFFLING MECHANISM FOR SEWING-MACHINES.

1,125,230.

Specification of Letters Patent.

Patented Jan. 19, 1915.

Application filed December 26, 1912. Serial No. 738,541.

To all whom it may concern:

Be it known that I, JOHN P. WEIS, a citizen of the United States, residing at Nyack, in the county of Rockland and State of New York, have invented certain new and useful Improvements in Top Feed or Ruffling Mechanism for Sewing-Machines, of which the following is a specification.

This invention relates to sewing machines, and more particularly to an improved top-feed or ruffling mechanism therefor, the object of the invention being to provide an improved top-feed or ruffling device for a long-arm top-shaft machine 15 that will have all of the movements of the ordinary four-motion feed heretofore used underneath the work.

A further object of the invention is the provision of an improved top ruffler or feed- 20 ing mechanism which will be simple in its construction, positive in all its movements and so organized as to be entirely out of the way of the operator, while at the same time means is provided whereby the throw of the 25 feed dog or ruffling blade may be instantly changed from one movement or throw to another while leaving the hands of the operator free.

A further object of the invention is the 30 provision of a top-feed or ruffling device for a top-shaft long-arm machine which will be operated entirely by and derive all its movements from said top shaft, so that the feed or ruffling blade will be actuated in a 35 four-motion path opposite to that of the main or bottom-feed, and in which improvement yielding means is provided for regulating the pressure of the top-feed on the work.

40 In the drawings accompanying and forming part of this specification, Figure 1 is a side view illustrating the ruffling device attached to a long-arm top-shaft machine; Fig. 2 is a top plan view of Fig. 1; Fig. 3 is an end view of Figs. 1 and 2 looking in the direction of the arrow in Fig. 2; Fig. 4 is a detail end view of the connecting means between the main driving shaft and the rock shaft; Figs. 5, 6 and 7, are detail views of 45 the crank end of the main driving shaft; Figs. 8 and 9 are detail views of the feed bar with a feed dog attached thereto in different positions relatively to the presser-foot; and Figs. 10 and 11 are detail views

of the same feed bar with a ruffling blade attached thereto in different positions relatively to the presser-foot. 55

Similar characters of reference indicate corresponding parts in the different figures of the drawings. 60

The arm of the machine is represented by dotted lines 1, and through this arm the top shaft 2 extends. This shaft has means, such as the cranks 3, for rotating the same. Secured to one end of the shaft 2 is a slotted disk 4, which carries an adjustable stud 5 on which is a sleeve or bushing 6 secured thereto by a nut 7, thus forming an adjustable crank. This disk 4 is detachably secured to the shaft 2 by a screw 51 tapped 70 into the shank 52 of the disk 4.

Connected with the bushing 6 is an arm 9, the end 10 of which is, by a screw 11, pivotally connected to a block 12 mounted for sliding movement on a curved arm 13. 75 A suitable spring 12' is provided to maintain this block in one position. Tapped in the screw 11 is a smaller screw 14 for the connection of a rod 15 leading to a floor treadle or knee shift to be operated from 80 underneath the table. Carried by a fixed bracket 20 is a post 18 on which is mounted a pair of adjustable stops 16 and 17, each having a projection 19 to coöperate with the end of hub 10 and so limit the up-and-down movement of the arm 9 and therefore the throw of the rock shaft 22. Carried by the bracket 20 is one end of a shaft 22, the opposite end of which is supported adjacent to the head of the machine by a bracket 90 24. The curved arm 13 is secured to the end of this shaft 22 in any suitable manner so that the shaft is rocked in its bracket bearings 20 and 24. Loosely mounted on this shaft 22, at its forward end adjacent to 95 the bracket 24, is a two-arm lever 30, one arm 27 of which terminates in a hook 28 while the other arm 26 has an opening to receive the end of a spring 31 held in working position by means of nuts 32. This 100 spring has several coils 33 of suitable diameter and a stem 34 secured in a connection 35, which has a strap 36 encircling an eccentric 37 forming a part of the needle driving crank 38 secured to the main shaft 2 in 105 any suitable manner.

A lifting motion is transmitted by the mechanism just described through the arms

26 and 27 of the lever 30 to the feed bar 40 as the hook 28 of the arm 27 receives the circular end 39 of this feed bar 40 which extends downward and is connected by a link 5 42 with the end of a connection 46 which is rigidly secured, as at 47, to the rock shaft 22, and this means causes the feed bar 40 to swing back and forth by reason of the rock shaft 22, the curved arm 13, the block 12 and 10 the arm 9. The end of the feed bar 40 is shaped to receive a feed dog 48 or a ruffling blade 49. The curved arm 13 gives the feed stroke to the feed dog 48 or the ruffling blade 49, either of which may be adjusted vertically in the feed bar by means of the slot 50 and screw 44. Thus it will be seen 15 that the forward and backward swinging movement of the feed bar 40 is obtained through the rock shaft 22 and the linkage 20 connection 46 and 42 from the main driving shaft by means of the curved arm 13, slide block 12 and connecting arm 9 hereinbefore described, while the rising and falling movement of this feed bar is obtained from the 25 main driving shaft through the medium of the eccentric, the cushion spring 33 and the two arms 26 and 27 of the lever 30 in a manner which will be readily understood. The hook 28 and end 39 thus form what may be 30 considered a ball and socket joint.

From the foregoing it will be observed that the rock shaft 22 being carried by fixed brackets therefor has a fixed axis and that the arm 27 of the two-armed lever 30 is mounted at one end on this fixed axis while its opposite end suspends the feed bar so that it directly carries such feed bar.

From the foregoing it will be observed that a very simple, durable and effective top-40 feed or ruffling device having the same movements as the lower feeds heretofore used is obtained, and that various shapes or combination of feeds may be used in the present improvement, at the back of the 45 needle, in front thereof or on either side.

It is very essential to provide means whereby the rising and falling motion of the feed may be lifted out of effective position by some means connected with the presser-foot mechanism, so that when the presser-foot is raised from the work to remove or replace it the feed will also be lifted to permit this. Clamped to the presser-foot bar 57 by screws 60 is the lifting collar 58, having a 50 part 59 extending through the back wall of the head, see Figs. 2 and 3, and co-operating with this collar is the usual hand or foot lifting device. A portion of this collar 58 projects laterally, as at 61, and extends forward, as at 62, underneath the hook 28, see Fig. 3, so that when the presser-foot is lifted as shown in Fig. 3 this end 62 contacts with and lifts the lever arm 27 and thereby the feed bar 40 sufficient 60 to clear the work. Should the machine be

operated for several revolutions while the presser-foot is so lifted the coils 33 of the spring will absorb the movement of the eccentric and the connection 35 so that there will be no up-and-down movement of the feed bar 40 at this time, as such bar 40 will simply have its in-and-out or swinging movement.

It will of course be understood that the various details may be more or less modified without departing from the spirit or scope of this invention, and that the term "feed bar" as used in the claims is not necessarily limited to a bar carrying a feed dog, but is intended to include within its scope a bar 75 which may also support a ruffling blade.

I claim as my invention:

1. In a sewing machine, the combination of a top driving shaft, a rock shaft adjacent thereto, connecting means between said shafts for actuating the rock shaft, a hanging feed bar suspended above the work, and a lever system including a movable arm mounted on a fixed axis and operated by and deriving all of its movements from said top 85 driving shaft, said arm having connection with the upper terminus of and suspending said hanging feed bar and whereby rising and falling and swinging movements are imparted to said hanging feed bar.

2. In a sewing machine, having an overhanging arm, the combination of a top driving shaft located therein and a rock shaft adjacent thereto, connecting means between said shafts for actuating the rock shaft, a hanging feed bar suspended above the work and adapted to receive interchangeably a feed dog or a ruffling blade, means for imparting a rising and falling movement to the feed bar, and means for 100 imparting a swinging movement to said bar, one of said means connected to the rock shaft and the other to the top driving shaft, and both of said means deriving all of their movements from said top driving shaft.

3. In a sewing machine having an overhanging arm, a top driving shaft carried thereby and normally rotatable in the same direction, the combination of a rock shaft, means connecting said rock shaft with the 110 driving shaft for rocking said rock shaft, a hanging feed bar suspended above the work and adapted to receive interchangeably a feed dog or a ruffling blade, means connected with said rock shaft for imparting a swinging movement to said feed bar, and means connected with said driving shaft for imparting a rising and falling movement to said feed bar, said feed bar deriving all of its movements from said top driving shaft.

4. In a sewing machine having an overhanging arm, a top driving shaft carried thereby and normally rotatable in the same direction, the combination of a rock shaft, means connecting said rock shaft with the 120

driving shaft for rocking said rock shaft, a hanging feed bar suspended above the work and adapted to receive interchangeably a feed dog or a ruffling blade, means connected 5 with said rock shaft for imparting a swinging movement to said feed bar, and means connected with said driving shaft for imparting a rising and falling movement to said feed bar and including a cushioning 10 spring, said feed bar deriving all of its movements from said top driving shaft.

5. In a sewing machine having an over-hanging arm, a top driving shaft carried thereby and normally rotatable in the same 15 direction, the combination of a rock shaft, means connecting said rock shaft with the driving shaft for rocking said rock shaft, a hanging feed bar suspended above the work and adapted to receive interchangeably a 20 feed dog or a ruffling blade, means connected with said rock shaft for imparting a swinging movement to said feed bar, and means connected with said driving shaft for imparting a rising and falling movement to 25 said feed bar and including a coiled cushioning spring, said feed bar deriving all of its movements from said top driving shaft.

6. In a sewing machine having an over-hanging arm, a top driving shaft carried 30 thereby and normally rotatable in the same direction, the combination of a rock shaft, means connecting said rock shaft with the driving shaft for rocking said rock shaft, a hanging feed bar suspended above the work 35 and adapted to receive interchangeably a feed dog or a ruffling blade, means connected with said rock shaft for imparting a swinging movement to said feed bar, and means connected with said driving shaft for imparting a rising and falling movement to 40 said feed bar, said means comprising a two-arm lever and a linkage connection below the same with said feed bar, said feed bar deriving all of its movements from said top driving shaft.

7. In a sewing machine having an over-hanging arm, a top driving shaft carried thereby and normally rotatable in the same 45 direction, the combination of a rock shaft, means connecting said rock shaft with the driving shaft for rocking said rock shaft, a hanging feed bar suspended above the work and adapted to receive interchangeably a 50 feed dog or a ruffling blade, means connected with said rock shaft for imparting a swinging movement to said feed bar, and means connected with said driving shaft for imparting a rising and falling movement to said feed bar, said means comprising a two-arm lever and a linkage connection below the same with said feed bar, one of said 55 lever arms and the feed bar having a ball and socket connection.

8. In a sewing machine having an over-hanging arm, a top driving shaft carried

thereby and normally rotatable in the same direction, the combination of a rock shaft, means connecting said rock shaft with the driving shaft for rocking said rock shaft, a hanging feed bar suspended above the work 70 and adapted to receive interchangeably a feed dog or a ruffling blade, means connected with said rock shaft for imparting a swinging movement to said feed bar, means connected with said driving shaft for imparting a rising and falling movement to 75 said feed bar, said means comprising a two-arm lever and a linkage connection below the same with said feed bar, one of said lever arms and the feed bar having a ball and 80 socket connection, and means for limiting the throw of said rock shaft.

9. In a sewing machine having an over-hanging arm, a top driving shaft carried thereby and normally rotatable in the same 85 direction, the combination of a rock shaft, means connecting said rock shaft with the driving shaft for rocking said rock shaft, a hanging feed bar located above the work and adapted to receive interchangeably a feed dog 90 or a ruffling blade, means connected with said rock shaft for imparting a swinging movement to said feed bar, means connected with said driving shaft for imparting a rising and falling movement to said feed bar, said 95 means comprising a two-arm lever and a linkage connection below the same with said feed bar, one of said lever arms and the feed bar having a ball and socket connection, and adjustable means for limiting the 100 throw of said rock shaft.

10. In a sewing machine having an over-hanging arm, a top driving shaft carried thereby and normally rotatable in the same direction, the combination of a rock shaft, 105 means connecting said rock shaft with the driving shaft for rocking said rock shaft, a hanging feed bar suspended above the work and adapted to receive interchangeably a feed dog or a ruffling blade, means connected with 110 said rock shaft for imparting a swinging movement to said feed bar, means connected with said driving shaft for imparting a rising and falling movement to said feed bar, and means for raising the 115 feed bar, said feed bar deriving all of its movements from said top driving shaft.

11. In a sewing machine having an over-hanging arm, a top driving shaft carried thereby and normally rotatable in the same 120 direction, the combination of a rock shaft, means connecting said rock shaft with the driving shaft for rocking said rock shaft, a hanging feed bar suspended above the work and adapted to receive interchangeably a feed dog or a ruffling blade, means connected with 125 said rock shaft for imparting a swinging movement to said feed bar, means connected with said driving shaft for imparting a rising and falling movement to said feed bar, and means for 130 raising the feed bar, said feed bar deriving all of its movements from said top driving shaft.

1. said feed bar, a presser-foot, and means connected therewith for raising it and also raising the feed bar.
2. In a sewing machine, the combination with the driving shaft, of a rock shaft, means connecting the driving shaft with the rock shaft and comprising a curved arm connected with the rock shaft, a sliding block mounted thereon and an arm connecting said block with the driving shaft, adjustable means for limiting the movement of said sliding block, a two-arm lever supported for swinging movement, a hanging feed bar having a ball and socket connection with one of the arms of said lever and suspended above the work, linkage connection between said feed bar and rock shaft, and a spring cushioned eccentric connection between one of said arms and the driving shaft whereby rising and falling and swinging movements are imparted to said feed bar.
3. In a sewing machine, the combination with the driving shaft, of a rock shaft, means connecting the driving shaft with the rock shaft and comprising a curved arm connected with the rock shaft, a sliding block mounted thereon and an arm connecting said block with the driving shaft, adjustable means for limiting the movement of said sliding block, a two-arm lever supported for swinging movement, a hanging feed bar having a ball and socket connection with one of the arms of said lever and suspended above the work, linkage connection between said feed bar and rock shaft, a spring cushioned eccentric connection between one of said arms and the driving shaft whereby rising and falling and swinging movements are imparted to said feed bar, and means in position to engage one of the arms of said lever for raising and lowering said feed bar.
4. In a sewing machine, the combination with the driving shaft, of a rock shaft, means connecting the driving shaft with the rock shaft and comprising a curved arm connected with the rock shaft, a sliding block mounted thereon and an arm connecting said block with the driving shaft, adjustable means for limiting the movement of said sliding block, a two-arm lever supported for swinging movement, a hanging feed bar having a ball and socket connection with one of the arms of said lever and suspended above the work, linkage connection between said feed bar and rock shaft, a spring cushioned eccentric connection between one of said arms and the driving shaft whereby rising and falling and swinging movements are imparted to said feed bar, and means in position to operate adjacent to the ball and socket connection of the feed bar for raising and lowering said feed bar.
5. In a sewing machine, the combination of a driving shaft, a rock shaft, a curved arm carried by said rock shaft, a sliding block mounted on said arm, a connection between said block and the driving shaft, adjustable means for limiting the movement of said block, means for shifting said block on its arm, a hanging feed bar located above the work, and means connecting said rock shaft with the feed bar for imparting swing-ing movement thereto.
6. In a sewing machine, the combination of a driving shaft, a rock shaft, a curved arm carried by said rock shaft, a sliding block mounted on said arm, a connection between said block and the driving shaft, adjustable means for limiting the movement of said block, means for shifting said block on its arm, a hanging feed bar located above the work, means connecting said rock shaft with the feed bar for imparting swing-ing movement thereto, and means for im-parting to said feed bar a rising and falling movement.
7. In a sewing machine, the combination of a driving shaft, a rock shaft, a curved arm carried by said rock shaft, a sliding block mounted on said arm, a connection between said block and the driving shaft, adjustable means for limiting the movement of said block, means for shifting said block on its arm, a hanging feed bar located above the work, means connecting said rock shaft with the feed bar for imparting swing-ing movement thereto, and means for im-parting to said feed bar a rising and falling movement.
8. In a sewing machine, the combination of a driving shaft, a rock shaft, a curved arm carried by said rock shaft, a sliding block mounted on said arm, a connection between said block and the driving shaft, adjustable means for limiting the movement of said block, means for shifting said block on its arm, a hanging feed bar located above the work, means connecting said rock shaft with the feed bar for im-parting swinging movement thereto, and means for im-parting to said feed bar a rising and falling movement, said means having connection with the driving shaft.
9. In a sewing machine, the combination of a driving shaft, a rock shaft, a curved arm carried by said rock shaft, a sliding block mounted on said arm, a connection between said block and the driving shaft, adjustable means for limiting the movement of said block, means for shifting said block on its arm, a hanging feed bar located above the work, means connecting said rock shaft with the feed bar for im-parting swinging movement thereto, and means for im-parting to said feed bar a rising and falling movement, said means having connection with the driving shaft.
10. In a sewing machine, the combination of a driving shaft, a rock shaft, a curved arm carried by said rock shaft, a sliding block mounted on said arm, a connection between said block and the driving shaft, adjustable means for shifting said block on its arm, a hanging feed bar located above the work, means connecting said rock shaft with the feed bar for im-parting swinging movement thereto, and means for im-parting movement thereto to raise and lower the feed bar.

20. In a sewing machine, the combination of a driving shaft, a rock shaft, a curved arm connected to said rock shaft, a sliding block mounted on said arm, a connection between said block and said driving shaft for oscillating said arm and thereby rocking said rock shaft, a two-arm lever supported for swinging movement, a coiled spring connected with one of the arms of said lever and having an eccentric connection with said driving shaft, a feed bar suspended above the work and adapted to interchangeably receive a feed dog or a ruffling blade and having a hinge connection with the other arm of said lever, and a linkage connection between said feed bar and the rock shaft whereby a rising and falling and swinging movement is imparted to the feed bar from the driving shaft. 70
- 10 21. In a sewing machine, the combination of a driving shaft, a rock shaft, a curved arm connected to said rock shaft, a sliding block mounted on said arm, a connection between said block and said driving shaft for oscillating said arm and thereby 75
- 15 25 25 by rocking said rock shaft, a two-arm lever supported for swinging movement, a coiled spring connected with one of the arms of said lever and having an eccentric connection with said driving shaft, a feed bar suspended above the work and adapted to interchangeably receive a feed dog or a ruffling blade and having a hinge connection with the other arm of said lever, and a linkage 80
- 30 35 35 connection between said feed bar and the rock shaft whereby a rising and falling and swinging movement is imparted to the feed bar from the driving shaft, and adjustable means for limiting the throw of said rock 85
- 40 shaft. 22. In a sewing machine, the combination of a driving shaft, a rock shaft, a curved arm connected to said rock shaft, a sliding block mounted on said arm, a connection 90
- 45 between said block and said driving shaft for oscillating said arm and thereby 95
- 50 55 55
- 55 60 60
- 65 65
22. In a sewing machine, the combination of a driving shaft, a rock shaft, a curved arm connected to said rock shaft, a sliding block mounted on said arm, a connection between said block and said driving shaft for oscillating said arm and thereby 100
- 65 70 70
- 75 80 80
- 85 90 90
- 95 100 100
- 105 110 110
- 115 120 120
- 125 130 130
23. In a sewing machine, the combination of a driving shaft, a rock shaft, a curved arm connected to said rock shaft, a

- comprising a two-armed lever supported by the rock shaft, an eccentric carried by the top shaft and a coil-spring connecting said eccentric with one of the arms of said lever.
- 5 27. In a sewing machine having an overhanging arm and a top driving shaft located therein and normally rotatable in the same direction, the combination of a rock shaft supported adjacent thereto, means connecting said rock shaft with the driving shaft, a hanging feed bar suspended above the work, means connecting said feed bar with the rock shaft, and means including a movable arm mounted on a fixed axis, said 10 arm operated by and deriving all of its movements from said top driving shaft and connected to the upper terminus of said feed bar for connecting said feed bar with the driving shaft and whereby rising and falling 15 and swinging movements are imparted to the feed bar.
28. In a sewing machine having an overhanging arm and a top driving shaft located therein and normally rotatable in the same 20 direction, the combination of a rock shaft supported adjacent thereto, means connecting said rock shaft with the driving shaft, a hanging feed bar suspended above the work, means connecting said feed bar with the 25 rock shaft, means including a two-armed swinging lever mounted on a fixed axis, one arm of said lever connected to the upper terminus of said feed bar, and means including an eccentric connection between the 30 driving shaft and the other arm thereof and whereby rising and falling and swinging movements are imparted from the driving shaft to the hanging feed bar.
29. In a sewing machine having an overhanging arm and a top driving shaft located therein and normally rotatable in the same direction, the combination of a rock shaft supported adjacent thereto, means connecting said rock shaft with the driving 35 shaft, a suspended feed bar located above the work, means connecting said feed bar with the rock shaft, and means connecting said feed bar with the driving shaft for imparting to the feed bar a rising and falling 40 and swinging movement, said means including a two-armed swinging lever, a linkage 45
- connection and a spring cushioned eccentric connection with the driving shaft.
30. The combination with the overhanging arm of a sewing machine and a top driving shaft located therein and normally rotatable in the same direction, of a rock shaft supported adjacent thereto, a hanging feed bar located above the work, means connecting said feed bar with the rock shaft, swinging means connected with said feed bar, and a coiled spring connected with said swinging connecting means and having one end connected to the driving shaft whereby rising and falling and swinging movements 50 will be imparted to the feed bar.
31. In a sewing machine, the combination of a top driving shaft, a rock shaft located adjacent thereto and connected therewith for actuation thereby, a hanging feed bar suspended above the work, means connected with the rock shaft for imparting a swinging movement to said feed bar, an eccentric carried by the top driving shaft, means supported by the rock shaft and connected with 55 the feed bar, and a spring connecting said eccentric and said last means for operating the latter thereby to impart a rising and falling movement to said feed bar.
32. In a sewing machine, the combination of a driving shaft, a hanging feed bar suspended above the work, means for imparting a swinging movement thereto, means for imparting a rising and falling movement thereto, and a coil-spring connected with the 60 driving shaft and with one of said means and constituting the means for imparting to one of said means all of its movements from the driving shaft.
33. In a sewing machine, the combination of a driving shaft, a hanging feed bar suspended above the work, means for actuating the same from the driving shaft, and a coil-spring connected with said driving shaft and with the feed bar actuating means for 65 imparting movement to the latter.
- Signed at Utica, New York, this 14th day of December, 1912.
- JOHN P. WEIS.
